UNITED STATES PATENT OFFICE.

SAMUEL G. CRANE, OF TOLEDO, OHIO, ASSIGNOR TO TOLEDO SCALE COMPANY, OF TOLEDO, OHIO, A CORPORATION OF NEW JERSEY.

ELECTRIC-CHECK-PRINTING SCALE.

Application filed November 21, 1919. Serial No. 339,688.

To all whom it may concern:

Be it known that I, SAMUEL G. CRANE, a citizen of the United States, residing at Toledo, in the county of Lucas and State of Ohio, have invented certain new and useful Improvements in Electric-Check-Printing Scales, of which the following is a specification.

This invention relates to weighing scales, and more particularly to automatic check printing scales. While inventions of scales of this type have heretofore been made, it is believed that no practical scale has heretofore been devised which will automatically issue a printed check of the unknown weight of the commodity being weighed without the aid of a manual operation.

The principal object of this invention is to provide a scale which will automatically determine the weight, print the same upon a check, and issue the check by means entirely within the scale itself, the only operation effected by the operator being the placing of the commodity upon the platform. Thus in stores and shops where commodities of unknown weight are continually being placed upon the scale platter my improved scale is particularly adapted, and also in factories where parts of machinery and the like must be accurately measured by the weight thereof, as when operated in connection with a conveyor of any familiar type, and the successive commodities may be weighed and printed records of the weight issued in rapid succession without the assistance or attendance of a weight checking clerk. It will be obvious that the scale is also adapted for many and various types of weighings.

Another object of my invention is to provide a novel mechanism for so timing the operation of the printing mechanism that said mechanism will not be actuated until after the weighing operation is completed and the weighing parts of the scale are at rest.

With the above and other objects in view which will readily appear as the invention is better understood, my invention consists in the novel construction, combination and arrangement of parts to be hereinafter more fully described and particularly pointed out in the appended claims.

Reference is to be had to the accompany-

ing drawings illustrating a preferred embodiment of my invention and wherein similar reference numerals designate similar parts throughout the several views.

In the drawings:

Figure 1 is a front elevation of my improved check-printing scale;

Figure 2 is a rear elevation thereof, parts being omitted for clearer illustration of the remaining elements;

Figure 3 is an enlarged fragmentary rear elevation of the check-printing, feeding and cutting mechanism;

Figure 4 is a detail edge view of the indicating mechanism and associated parts;

Figure 5 is a front elevation of the disc, partly broken away to show the rotating switch in closed position;

Figure 6 is a similar view showing this switch in open position;

Figure 7 is a side elevation of this switch and associated parts;

Figure 8 is a perspective view of the switch mechanism operating the locking and reversing devices;

Figure 9 is a detail sectional view through the hub of the driving gear taken substantially on the line 9—9 of Figure 7;

Figure 10 is a rear elevation of the resilient switch member and associated parts;

Figure 11 is a perspective view thereof;

Figure 12 is a rear elevation with portions omitted to more clearly portray the remaining parts in detail;

Figure 13 is a similar rear elevation of the scale showing other elevations in detail;

Figure 14 is a sectional view on the line 14—14 of Figure 12;

Figure 15 is a detail perspective view of the motor reversing switch;

Figure 16 is a rear elevation of the pole-changing device;

Figure 17 is a detail side view of the mounting of the magnetic printing hammer and associated parts;

Figure 18 is a detail perspective view of the actuating means for the printing mechanism;

Figure 20 is a diagrammatic view of the wiring of the scale; and

Figure 21 is a detail section on line 21—21 of Figure 13, showing the arrangement of parts for printing the weights.

While my invention is adaptable to many

different styles and makes of scales, whether the load-offsetting device therein be spring, lever or pendulum, the present embodiment is adapted for use in connection with dial 5 scales where an indicating hand is adapted to swing over a graduated chart to indicate the weight of the commodity being weighed.

In the drawings, 1, designates the usual 10 scale housing mounted upon a column 2 which connects with the base and platform levers (not shown). As the weighing or load-offsetting mechanism of the scale forms no part of the present invention, I will describe it briefly, the mechanism being preferably of the type adapted to weigh comparatively heavy loads. The pendulum counterbalance mechanism herein illustrated is one that has been found to successfully 15 demonstrate the capabilities of this invention, and shows a double pendulum scale of a well-known type adapted to be suitably connected with a scale lever 3 fulcrumed within the upper portion of the column 2 20 through the medium of a steelyard rod 4 and so arranged and positioned that upon the placing of a load upon the scale platform the pendulums will be swung upwardly into a position counterbalancing the 25 weight of the load on the platform, the pendulums falling again to their normal or zero position when the load is removed from the scale platform. As herein shown, the pendulum counterbalance mechanism comprises 30 a pair of oppositely-disposed pendulums 5, each of which comprises supporting segments 6 secured on transverse shafts, and the two shafts are connected by crossbars 7, the segments 6 being suspended from the lower 35 ends of flexible supporting ribbons secured at their upper ends upon the framework of the scale. Intermediate the supporting segments of each pendulum is a somewhat larger segment 8, which is also fixed to 40 the transverse shaft, said segment extending at its periphery between the pillars of the framework supporting the segments 6, and being connected to the upper end, as at 45 9, to a flexible metallic ribbon 10 which 50 extends over the arcuate face of the segment and is attached at its lower end to an equalizer bar 11. The construction of the two pendulums is substantially identical, and the ribbons 10 are connected to opposite 55 sides of the equalizer bar 11, which is centrally connected, as by the link 12, with the upper end of the steelyard rod 4, which, as before described, is connected with the lever 3.

60 In the operation of the scale, when a load is placed on the scale platform, a downward pull is exerted on the equalizer bar 11, which is transmitted through the ribbons 10 to the larger segments 8, causing a 65 swinging of the pendulums 5 so that the

pendulum weights are raised to a counterbalanced position. During the swinging movement of the pendulums to offset the weight of the load, the crossbars 7 are moved vertically upward, and through the medium 70 of this vertical movement of the crossbars the weight indication on the dial is effected, the crossbars 7 carrying a vertically disposed rack 13 meshing with a pinion 14 fixed upon the indicator shaft 15 carrying the 75 index hand 16. The indicator shaft 15 is mounted concentrically of the dial 17 having the desired weight graduations suitably inscribed thereon, as, for example, in the manner illustrated in Fig. 1, with which graduations the index hand 16 co-operates in indicating the weight of the load being weighed. This pendulum counterbalance mechanism is sufficient to independently offset the weight of all loads within the capacity 80 of the dial.

Supported within the column 2 and cooperating with the scale beam pivoted therein is a timing switch mechanism, which, as will be apparent from the following description, comprises one of the important features of this invention. A resilient member 19 is securely fastened to one side of the column 2 and extends across the upper portion thereof, it being suitably shaped so as to provide an elongated opening surrounding portions of the scale mechanism extending through the column, such as the steelyard rod connecting the platform levers with the beam 3, etc. Mounted upon the free end of the resilient member 19 is a dash pot 20, the lower portion of which extends through an opening in the bracket 18, thereby permitting the dash pot to swing with this resilient member. Limiting means are preferably provided to prevent undue swinging movement of the dash pot and resilient member, as herein shown comprising adjusting screws 21 mounted in the member 19 adjacent the dash pot and adapted to contact the bracket 18 when the limit of the downward movement of the dash pot has been reached. A plurality of L-shaped guides 22 are adjustably mounted upon the column 2, the short arms of which are adapted to extend over the edge of the member 19 and limit the upward movement thereof. Secured within the column 2 and above the resilient member are brackets 23 in which is journaled a transverse rock-shaft 24 having needle point or other suitable anti-friction bearings and carrying a crank arm 25 which is pivotally connected to the resilient member 19 by the link 26, and a crank arm 27 of much greater length than the arm 25 and extending in the opposite direction, the outer extremity of which operates between the shorter arms of upper and lower contact levers 28 and 29 respectively fulcrumed between the vertical arms of a standard 30. The extremities of 100 105 110 115 120 125 130

the longer arms of the contact levers 28 and 29 are adapted to engage the upper and lower contact screws 31 and 32 carried by but insulated from the bracket 18. The upper lever 28 has its shorter arm operatively connected with a timing device 33, the purpose of which will appear in the following paragraph. The plunger of the dash pot 20 is operatively connected with the scale beam 3 by means of the plunger rod 20^a and serves to damp the vibratory movements of the delicate parts of the scale.

Thus, it will be apparent that while the weighing mechanism of the scale is in operation the scale beam 3 will be caused to vibrate, which will force the plunger to reciprocate within the oil cylinder of the dash pot. As the dash pot is suspended upon the free end of the resilient member 19, the action of the plunger in the oil will impart a vibrating movement to the dash pot which will cause the shaft 24 to be rocked by reason of the crank arm 25 and link 26. The rocking of the shaft 24 causes the free end of the crank arm 27 to alternately engage the shorter arms of the contact levers 28 and 29, and break the engagement of their longer arms with the contact screws 31 and 32. Thus, when the scale beam 3 is pulled downwardly, the dash pot 20 is moved correspondingly, causing the free end of the arm 27 to move upwardly and breaking the contact of the upper contact lever 28 with the contact screw 31. The shorter arm of this lever 28 is connected to the timing device 33 and retards the movement of the lever 28 in resuming its normal position in engagement with the contact screw 31 to permit the current of electricity to flow through the switch set up by the levers 28 and 29 and the contacts 31 and 32 respectively.

It is obvious that should the previously described switch mechanism alone be used, the circuit would be closed when the scale is at rest and no load upon the platform which would cause the printing mechanism to be actuated. In order to overcome this difficulty I provide in addition to this timing switch mechanism a master switch mechanism which is adapted to be closed only when a commodity is placed upon the platform of the scale, the arrangement being such that before the electrical current can operate the check-printing mechanism, both switches must be closed. This master switch is normally open and adapted to be closed upon the downward movement of the steelyard rod 4. This master switch comprises a switch arm 35 mounted upon but insulated from the frame of the scale and is normally held in a raised position by means of a lug 36 of insulating material carried by the steelyard rod. A contact screw 37 is positioned to engage the switch arm 35 when the

steelyard rod is moved downwardly, while a second contact screw 38 is normally in contact with a flexible switch arm 39 carried by said arm 35, as shown in Figs. 2 and 3.

Referring now to the check-printing mechanism which, as has been stated, is not actuated until the completion of the weighing operation and which includes means for rotating the driving mechanism for the printing disks proportionately to the rotation of the index hand 16 when indicating the weight of the commodity on the platform of the scale and means for stopping the rotation of said mechanism when the correct arrangement of type numerals is obtained. More specifically, this mechanism comprises a disk 40 fixedly mounted upon the indicator shaft 15 and having a rearwardly projecting stop arm 41 secured thereto in any suitable manner. This rearwardly-projecting arm 40 co-operates with a rotating switch 44 controlling the rotation of the large driving gear 42, which is mounted with its axis in alignment with the shaft 15 and provided with as many teeth as there are pounds indicated upon the dial 17. This rotating switch is normally closed and is broken when the gear 42 moves through a partial rotation corresponding to the movement of the index hand showing the weight of a commodity on the scale platform. This switch 44 comprises an insulating segment block 44' mounted upon a hub 45 of the driving gear 42 and secured to the gear in any suitable manner. A pair of spaced contacts 44^a and 44^b are secured to the peripheral face of the block 44', while a flexible switch member 44^c is secured to the contact 44^a and engages the contact 44^b, thereby normally keeping the switch closed. The free end of the switch member 44^c extends a certain distance above the contact 44^b in the path of travel of the arm 41. Mounted upon the hub 45 in the rear of the gear 42 are a pair of spaced contact rings 46 and 47 electrically connected with the contacts 44^a and 44^b respectively through wires 46^a and 47^a (see Figs. 5 and 9). Brushes 48 and 49 contact the rings 46 and 47 respectively. Mounted rearwardly of the rings 46 and 47 is a standard in which is journaled in suitable bearings a shaft 50 keyed to the hub 45 and having secured thereon a pair of timing cams 51 and 52, the purpose of which will appear later. Engaging the cam 51 is one end of a switch arm 53, the other end being pivoted to a standard 54, said arm normally being in contact with a contact screw 55 electrically connected with the switch contact screw 37 of the master switch. Electrically connected with the standard 54 is a pole-changing motor 56 which is provided with a pinion secured to the armature thereof for driving the gear 42. A switch member 63 (see Fig. 8) similar in construction

to the switch 53 comprises an arm 63^a, one end of which engages the cam 52 and is normally held in raised position, which forces the lower end of a right-angled arm thereof 5 to be out of engagement with a contact screw 64. Upon rotation of the gear 42 the cam 52 will be revolved, thereby lowering the arm 63^a and permitting the engagement of the right-angled arm with the contact screw 64, thereby permitting the current of 10 electricity to flow to a magnet 65 supported by the scale framework and in such position that when energized the magnet will attract the disk 40, thereby locking the index 15 hand and driving mechanism against rotation. (See Fig. 7.)

The printing disk mechanism may be of any familiar type, the embodiment herein shown being one form particularly adaptable for use in connection with the present 20 form of device. With particular reference to Figs. 3, 18 and 19, I have shown the printing mechanism as consisting of a plurality of disks 57 having numerals arranged 25 consecutively on the peripheries thereof and so arranged that upon rotation of the shaft 58 upon which the disks 57 are mounted, the numerals will be proportionately moved to indicate successive pounds and fractions 30 thereof. In order to provide means for such rotation of the disks 57 I have shown a pinion 59 secured upon the end of the shaft 58 and in mesh with the driving gear 42, which, as hereinbefore stated, is provided 35 with teeth in number corresponding to the capacity of the scale in pounds. Upon the opposite extremity of the shaft 58 I provide a star wheel 60, which, when engaged by the latch 61, serves as a stop for the printing 40 mechanism and serves to align the type numerals for clear printing. The arm of the latch 61 has one of its ends pivotally connected to the base of an electro-magnet 62, while the armature thereof is in such relation 45 to said arm that when the magnet is energized the arm will be lifted, thereby permitting the free end to be retracted from engagement with the star wheel. (See Figure 13.)

50 When a commodity is placed upon the platform of the scale the weighing mechanism is actuated as hereinbefore described to offset the weight of the load. As the shaft 15 is rotated, carrying with it the index hand 16 to indicate the weight of the load, the disk 40 is simultaneously rotated to position the stop arm 41. During this weighing operation the master switch 35 is closed but the timing mechanism, including the upper and 55 lower switch levers 28 and 29, which is in circuit with the switch 35 and check-printing mechanism, is open, thereby preventing the actuation of the driving gear 42 and associated mechanism until the weigh- 60

ing operation is completed and the index hand properly indicates the weight of the load on the platform. Upon completing this operation the scale beam 3 is brought to a standstill, thereby permitting the timing switch to close. The current then flows 70 from the service plug S located in the upper part of the scale housing and connected to a battery B or other source of electrical supply to the master switch 35 (which was closed as the steelyard rod 4 was 75 pulled downward to actuate the pendulums), thence to the switch 53 electrically connected with the driving motor 56 and to the magnet 62, which lifts the latch 61 from engagement with the star wheel 60, releasing 80 the gear wheel 42 and associated mechanism. The motor 56 drives the large gear wheel 42 and causes the shaft 50 to revolve, and the cam disks 51 and 52 which are secured on the shaft to operate the switch arms 53 and 63^a respectively. The cam 52 is so timed that upon the beginning of the rotation of the gear 42 the switch arm 63^a will be lifted, thereby closing the circuit in the switch which permits the magnet 65 to become energized, thereby locking the disk 40 and the weighing mechanism of the scale against movement. It will be remembered that the disk 40 carrying with it the stop arm 41 has been rotated correspondingly to the index hand so that the stop arm remains in transverse alignment with the index hand when indicating the weight of a commodity. When the disk 40 is locked by means of the magnet 65, the lug 41 provides 95 a stationary rearwardly-extending stop adapted to engage the upper end of the flexible switch member 44^c as the switch 44 revolves with gear 42, thereby opening the switch to stop the motor 56 and de-energizing the magnet 62, causing the latch 61 to re-engage the star wheel 60 to prevent movement thereof. As the latch 61 drops back into engagement with the star wheel 60 under tension of a spring 66, a circuit switch 10 67 is closed, thereby energizing a magnet 68, to the armature of which is connected an arm 69 having formed at the end thereof a hammer adapted to impinge a paper strip or card upon the type disks when the magnet is 11 energized. Carried by the arm 69 is a finger 70 adapted to close a circuit switch 71 as the arm is attracted to the magnet 68, thereby causing a magnet 72 to become energized, the armature 73 of which is arranged to actuate a pole-changing device electrically connected to the motor 56 for reversing the rotation thereof, returning the gear wheel 42 and associated mechanism to zero position. Simultaneously the armature closes a switch 12 for energizing the check-issuing mechanism as hereinafter described.

After the printing operation is effected,

as has been described, it is necessary to feed the strip along a certain distance and then sever it from the main roll of paper to issue the printed check. Referring particularly to Figs. 3, 12 and 13, it will be noted that adjacent the printing mechanism there is secured to the framework of the scale a suitable bracket 74 in which are journalled shafts 75 and 76 having keyed thereto feeding rollers 77 and 78 respectively, geared together to cause one of said rollers to revolve in a direction opposite to that of the other. Keyed to the lower shaft 76 is a pinion 79 in mesh with a vertically-disposed rack 80 slidably supported by the bracket 74 and normally held in a raised position by virtue of a spring 80^a. The lower extremity of the rack bar is formed as the core of a solenoid 81, which, as will be hereinafter explained, when energized effects a downward movement of the rack bar 80. Secured to the bracket 74 is a check-cutting member, positioned in a plane tangentially with the juncture of the two feeding rollers, and comprising a knife member 82 pivotally secured at one end to the bracket 74, while the other end is normally held in a raised position by reason of a coiled spring 82^a. Referring to Figs. 3 and 12 it will be noted, however, that provision has been made for means whereby the solenoid may be energized until the rack bar has completed its downward movement to sever the strip of paper from the roll. Secured to the rack bar 80 is an arm 83 adapted to engage a trip member 84 pivoted to an insulating member supported by said bracket 74. A switch lever 85 is pivotally mounted upon said insulating member and has one end provided with a contact point, preferably of platinum, adapted to engage a contact screw 86, but normally held out of engagement therewith by reason of a spring-pressed plunger 87 engaging the opposite and longer end of the lever 85. The trip member 84 is connected to the plunger 87 by means of a pin-in-slot connection and it is obvious that as the rack 80 is moved downwardly from its normal position (see FIG. 12), even to the slightest degree, the arm 83 will engage the trip member 84 which will withdraw the plunger 87 from engagement with the lever 85, thereby permitting the contact end of the lever, by reason of a coiled spring 88, to engage the contact screw 86. Pivotally supported by the insulating member is a trip lever 89, one arm of which is in the path of travel of a finger 90 carried by the upper end of the rack bar, and the other end thereof engaging the under side of the longer arm of the lever 85. Thus, after the rack has moved its full stroke downward, the finger 90 engages the end of the trip lever 89 which causes the longer end of the lever 85 to be raised and retained in that position by

means of the plunger 87 to break the circuit for energizing the solenoid 81 and associated mechanism.

Suitable means for inking the type may be employed, the embodiment shown herein being sufficiently adaptable to facilitate in an efficient operation of the machine. As shown in Fig. 13, a plurality of guide rollers 92 are mounted upon the framework, and passing around these rollers is an inked ribbon 93 which passes over the type bars and under the paper strip. Adjusting means such as shown at 94 may be employed to regulate the tension of the ribbon. Secured to one of the rollers is a ratchet and pawl 95 adapted to be engaged by a dog 96 carried by the gear wheel 42, whereby the ribbon is slightly moved over the printing discs upon every revolution of the gear wheel.

The mechanism for supplying the strip of paper 102 for the tickets comprises a reel 103 mounted on the scale frame and carrying a roll of paper guided over idler rollers 104, thence passing over printing wheels 57, between feed rollers 77 and 78, and under the knife 82, which severs the strip, the cut and printed ticket being guided by chute 105 to receiving pan 106 mounted on the column 2 of the scale.

In order that the operating mechanism may be automatically reset for the next weighing operation it is necessary to again change the circuits or rather set the pole-changing device to its original position. To accomplish this in an efficient manner (see Figs. 3 and 20) a trip lever 97 is pivoted to the frame 74 and normally urged downwardly by a spring 97^a, one end thereof being pivotally connected to the trip 73^a while the other end engages a latch 98 formed with a shoulder upon which the trip lever 97 rests after the rotation of the motor has been stopped and the poles reversed. A dog 100 is keyed to the shaft 50 and as the gear approaches the zero position of the scale on its return movement the dog 100 engages the latch 98 and releases the trip lever, causing the trip 73^a to rise, changing the poles to the original condition.

While it will be apparent that the illustrated embodiment of my invention herein disclosed is well calculated to adequately fulfill the objects and advantages primarily set forth, it is to be understood that the invention is susceptible to variation, modification and change without departing from the spirit and scope of the invention as set forth in the subjoined claims.

Having described my invention, I claim:

1. In a device for recording weights, in combination, weighing mechanism, printing mechanism, an electric circuit, means to open said circuit actuated upon vibratory movement of said weighing mechanism, said means acting to close said circuit upon ces. 120

sation of such vibratory movement, means controlled by said circuit for operating said printing mechanism, and means for holding said circuit open when said weighing mechanism is at zero position.

2. In a printing scale, in combination, automatic weighing mechanism, type-setting mechanism, printing mechanism, and means under control of the weighing mechanism for automatically actuating said type-setting and printing mechanism and means whereby the operation of said actuating means is delayed until said weighing mechanism comes to rest in weighing position.

15 3. In a printing scale, in combination, automatic weighing mechanism, type-setting and printing mechanism, and electrically-operated means under control of the weighing mechanism for automatically actuating said type-setting and printing mechanism and means whereby the operation of said actuating means is delayed until said weighing mechanism comes to rest in weighing position.

20 4. In a printing scale, in combination, automatic weighing mechanism, printing mechanism, and means for automatically actuating said printing mechanism when said weighing mechanism comes to rest in weighing position, said means including an electric circuit having a delaying switch therein, and means whereby said switch is closed only upon cessation of movement of said weighing mechanism.

25 5. In a printing scale, in combination, automatic weighing mechanism, printing mechanism, and means for automatically actuating said printing mechanism when said weighing mechanism comes to rest in weighing position, said means including a vibratory member, an electric circuit, and means to hold said circuit open during vibration of said member.

30 6. In a printing scale, in combination, automatic weighing mechanism, printing mechanism, and means for automatically actuating said printing mechanism when said weighing mechanism comes to rest in weighing position, said means including a vibratory member, a switch, means to open said switch upon movement of said vibratory member in one direction, and means acting to slowly close said switch upon movement of said vibratory member in the other direction.

35 7. In a printing scale, in combination, automatic weighing mechanism, printing mechanism, and means for automatically actuating said printing mechanism when said weighing mechanism comes to rest in weighing position, said means including a vibratory member, a pair of normally closed switches, one of which is opened by movement of said vibratory member in one direction and the other of which is opened by

movement of said vibratory member in the opposite direction.

8. In a printing scale, in combination, automatic weighing mechanism, printing mechanism, and means for automatically actuating said printing mechanism when said weighing mechanism comes to rest in weighing position, said means including a vibratory member, a pair of normally closed switches, one of which is opened by movement of said vibratory member in one direction and the other of which is opened by movement of said vibratory member in the opposite direction, one of said switches being connected to a retarding device.

9. In a printing scale, in combination, automatic weighing mechanism, printing mechanism, and means for automatically actuating said printing mechanism when said weighing mechanism comes to rest in weighing position, said means including a vibratory member, a pair of normally closed switches, one of which is opened by movement of said vibratory member in one direction and the other of which is opened by movement of said vibratory member in the opposite direction, one of said switches being connected to a dash pot retarding device.

10. In a printing scale, in combination, automatic weighing mechanism, printing mechanism, and means for automatically actuating said printing mechanism when said weighing mechanism comes to rest in weighing position, including a dash pot mounted upon a vibratory member, a switch, means to open said switch upon movement of said vibratory member in one direction, and means acting to slowly close said switch upon movement of said vibratory member in the other direction.

11. In a printing scale, in combination, automatic weighing mechanism, printing mechanism, and means for automatically actuating said printing mechanism when said weighing mechanism comes to rest in weighing position, including a dash pot mounted upon a vibratory member, an electric circuit, and means to hold said circuit open during vibration of said member.

12. In a printing scale, in combination, automatic weighing mechanism, printing mechanism, and means for automatically actuating said printing mechanism when said weighing mechanism comes to rest in weighing position, including a dash pot mounted upon a vibratory member, a pair of normally closed switches, one of which is opened by movement of said vibratory member in one direction and the other of which is opened by movement of said vibratory member in the opposite direction.

13. The combination in a scale, of weighing mechanism including a dash pot mounted upon a vibratory member, an electric circuit including a switch, means to open said

switch upon movement of the vibratory member in one direction, and means acting to slowly close said switch upon movement of said vibratory movement in the other 5 direction.

14. The combination in a scale, of weighing mechanism including a dash pot mounted upon a vibratory member, an electric circuit, and means controlled by the vibration 10 of said member to hold said circuit open during the vibration thereof.

15. The combination in a scale, of weighing mechanism including a dash pot mounted upon a vibratory member, an electric circuit including a pair of normally closed 15 switches, one of which is opened by movement of said vibratory member in one direction and the other of which is opened by movement of said vibratory member in the 20 opposite direction.

16. In a printing scale, in combination, weighing mechanism, a type-carrying device, means for setting said type-carrying device, comprising a motor, a circuit controlling said motor, means for closing said 25 circuit when said weighing mechanism comes to rest in weighing position, and means for opening said circuit when said type-carrying device reaches a position corresponding to the position of said weighing 30 mechanism.

17. In a recording scale, in combination, weighing mechanism, recording mechanism, a motor for setting said recording mechanism, 35 means controlled by said weighing mechanism for starting said motor, means whereby said starting means is actuated when said weighing mechanism is in weighing position, means controlled by said 40 weighing mechanism for stopping said motor when said recording mechanism is in recording position, and means for reversing said motor after the recording operation.

18. In a check printing scale, weighing 45 mechanism, mechanism set in operation by the weighing mechanism for printing characters on a strip of paper, and means for severing printed portions of said strip, comprising a solenoid and a severing blade operated thereby.

19. In a check printing scale, in combination, weighing mechanism, printing type, type-carrying mechanism, means actuated when said weighing mechanism comes to 55 rest in weighing position to move said type-carrying mechanism to a printing position corresponding to the position of said weighing mechanism, means controlled by said weighing mechanism for locking said type-carrying mechanism in such printing position, means actuated by the operation of said locking means for effecting an impression from said type upon a strip of paper, and means for returning said type-carrying 60 mechanism to its original position.

20. In a check printing scale, in combination, weighing mechanism, printing type, type-carrying mechanism, driving means actuated when said weighing mechanism comes to rest in weighing position to move said 70 type-carrying mechanism to a printing position corresponding to the position of said weighing mechanism, means controlled by said weighing mechanism for locking said type-carrying mechanism in such printing position, means actuated by the operation of said locking means for printing characters from said type upon a strip of paper, means for returning said type-carrying 75 mechanism to its original position, and means actuated upon operation of said printing means for severing the printed portion of said strip.

21. In a check printing scale, in combination, weighing mechanism, printing type, type-carrying mechanism, driving means actuated when said weighing mechanism comes to rest in weighing position to move said type-carrying mechanism to a printing position corresponding to the position of said 80 weighing mechanism, means operated upon such movement of said driving means to lock said weighing mechanism, means controlled by said weighing mechanism for locking said type-carrying mechanism in 85 such printing position, means actuated by the operation of said last-mentioned locking means for printing characters from said type upon a strip of paper, and means actuated by the operation of said printing 90 means for returning said type-carrying mechanism to its original position.

22. In a check printing scale, in combination, weighing mechanism, printing type, type-carrying mechanism, driving means actuated when said weighing mechanism comes to rest in weighing position to move said type-carrying mechanism to a printing position corresponding to the position of said 100 weighing mechanism, means operated upon such movement of said driving means to lock said weighing mechanism, means controlled by said weighing mechanism for locking said type-carrying mechanism in such printing position, means actuated by the operation of said last-mentioned locking means for printing characters from said type upon a strip of paper, and means actuated by the operation of said printing 105 means for returning said type-carrying mechanism to its original position.

23. In a check printing scale, in combination, weighing mechanism, printing type, type-carrying mechanism, driving means for said type-carrying mechanism, means to actuate said driving means operated by movement of said weighing mechanism from zero 110 115 120 125 130

- position, delaying means to prevent the operation of said driving means until said weighing mechanism has reached a position of equilibrium, means controlled by said weighing mechanism for stopping and locking said type-carrying mechanism in printing position, means actuated by the operation of said locking means for printing characters from said type upon a strip of paper, and means actuated by the operation of said printing means for releasing said locking means and setting said driving means in motion in reversed direction, thereby returning said type-carrying mechanism to its original position.

SAMUEL G. CRANE.
